UNITED STATES PATENT OFFICE

2,606,687

CLOSURE FOR FERMENTATION VESSELS

Josef Marek, Moravska Ostrava, Czechoslovakia

Application October 21, 1946, Serial No. 704,567
In Czechoslovakia June 21, 1945Section 1, Public Law 690, August 8, 1946
Patent expires June 21, 1965

1 Claim. (Cl. 220—45)

1

This invention relates to closures for fermentation vessels, preserving jars and like receptacles.

Besides the known glass closures which are adapted to be tightly inserted in the stopper of a fermentation or like vessel, it is known to construct closures and/or so-called fermentation caps which are capable of being used with various forms of vessels having widely different widths of neck. Such fermentation closures or caps are designed to prevent air or bacteria from entering said vessels and are attached by glue or other adhesive in an aperture in a parchment, paper or like cover which is tied or otherwise secured over the bottle or jar neck in similar manner to the closures of jam jars.

These known arrangements have the disadvantage that the fermentation closure or cap easily becomes loose under the influence of moisture and that particles of the adhesive material, by which they are secured in position, penetrate through the aperture in the parchment cover into the vessel and contaminate, or at any rate impair, the taste of the fermentation juices in the vessel.

Therefore, it is an object of this invention to provide a closure for use in connection with fermentation vessels which will overcome the above mentioned drawbacks.

It is another object of this invention to provide a closure for fermentation vessels which will maintain the vessel properly sealed and will not be affected by moisture surrounding the closure.

These and other objects and advantages of the invention will appear more clearly from the following specification in connection with the accompanying drawings which show an embodiment of the invention.

Referring to the drawings in detail, the structure shown therein illustrates the closure or cap according to the invention as comprising two mutually connectible parts, namely an upper part 1 having an externally threaded extension 1', and a lower annular part 2 which is internally threaded and is adapted to be screwed on to the extension 1'. The upper part 1 is moreover provided with an annular cavity 3 adapted to be filled with liquid to form a liquid seal and to receive a cup-shaped cap 4 which is adapted to cover a central axial duct 5 formed in said closure member.

The closure or cap 1 with the extension 1' is fitted in a central aperture 8 in a sheet 6 of parchment or other suitable material, which is tied or otherwise secured over the mouth of the vessel 7 in the usual manner. The aperture 8 in the cover 6 is of such a diameter that the

2

extension 1' of the upper part 1 of the closure or cap fits closely therein so that when the lower part 2 of the closure or cap is screwed on to the extension 1', the edge of the cover 6 around the aperture 8 is clamped between the annular member 2 and the upper part 1 of the closure or cap. The upper part 1 is provided with an outwardly projecting flange portion to ensure that a relatively large area of the cover 6 is clamped between said upper and lower parts 1 and 2 of said closure or cap.

With a closure or cap according to the invention carbon dioxide and other gases escaping from the fermenting liquid in the vessel 7 pass through the central duct 5 of the closure or cap and thence escape into the atmosphere in the form of bubbles through the liquid seal 3. As will be clearly understood, the tightness of the closure or cap according to the invention is in no way affected or influenced by moisture or other atmospheric conditions. In certain circumstances the tightness of the closure or cap can be enhanced by suitably arranging a washer or other packing, such as cork, between the parts 1 and 2.

It must be clearly understood that the parts 1 and 2 of the cap or closure may be made of any suitable material, and the closure or cap, as a whole, may be made of any suitable size appropriate to the various sizes of vessel with which it is to be used.

While the invention has been described in connection with a specific embodiment thereof, it is, of course, understood that the invention is not limited by the particular structure shown in the drawing, but comprises any modifications within the scope of the appended claim.

What I claim and desire to secure by Letters Patent is:

40. A closure for fermentation vessels which is adapted to provide a cover for vessels having openings of different diameters, said closure comprising a sheet of parchment which is adapted to be secured over the mouth of the vessel, an opening in said parchment, a stopper having abutment means disposed in said parchment opening, clamping means carried by said stopper cooperating with said abutment means for securing the stopper to said parchment to provide a unitary cover structure, said stopper having a passageway therethrough for the escape of fermentation gases, an annular cavity in said stopper concentric with said passageway and forming a reservoir containing a liquid, and a cap closing the passageway through said stopper, said cap

comprising an inverted cup-shaped member, the peripheral wall of said cup-shaped member being partly submerged in said liquid and being generally spaced from the walls of said annular cavity.
